PRESS TIMER

Russell G. McLagan, Cincinnati, Ohio, assignor
to The American Laundry Machinery Company,
Norwood Station, Cincinnati, Ohio, a corpora-
tion of Ohio

Application August 14, 1947, Serial No. 768,670

1 Claim. (Cl. 192—138)

1

This invention relates to timing devices, such as are employed for timing the operation of machines or machine parts.

One example of such use is in the operation of presses for pressing or ironing articles of wearing apparel such as men's shirts or outer garments, such as coats and trousers. Such machines may be operated and controlled by fluid pressure. The operator actuates a controlling valve to close the press, the control system including means for maintaining the operating fluid pressure. When the pressing operation is concluded, the pressure is relieved or evacuated and the press opens.

The present invention provides automatic timing means, set into operation when the operator causes the press to close, which causes it to open after the lapse of an interval the duration of which may be varied as desired. When the press opens the timing parts automatically return to their original positions ready for another operation.

One object of the present invention is to provide improved timing means of the character described which is of simple construction, is dependable in operation and is not likely to get out of order in service.

Another object is to provide improved timing means which can be made, assembled and operated in multiple form, capable of simultaneously controlling or handling several machines or operations.

A further object is to provide improved timing mechanism in which a single pilot motor can be made to control several machines or devices.

Still another object is to provide improved timing mechanism including a friction clutch capable of slipping when the timer performs its actuating function, thus preventing stalling of the pilot motor.

A further object is to provide improved timing mechanism which includes automatic resetting means which is reliable in operation and which, also, is unaffected by adjustment of timer for different time periods.

Further objects of the invention in part are obvious and in part will appear more in detail hereinafter.

In the drawings, which represent one suitable embodiment of the invention, Fig. 1 is a front elevation, with parts broken out and in section;

Fig. 2 is a sectional elevation on the line 2—2, Fig. 1;

Fig. 3 is a detail section, on a larger scale, on the line 3—3, Fig. 2; and

2

Fig. 4 is a diagram showing the timer applied for the control of a garment press.

Referring to Fig. 1, the timing mechanism or device shown includes a base 10 designed for mounting upon a suitable support and to carry the operating mechanism. This includes a shaft 11 journaled in bearing supports 12 and driven through conventional speed reducing gearing 13 by a small pilot motor 14. This rotates constantly at uniform speed, the reducing gearing cutting the speed down to a low value, say 1 or 2 R. P. M.

Shaft 11 operates the timing mechanism which may be a single mechanism or include a plurality thereof spaced at intervals along the shaft, but all operated thereby and each of several being effective or operating independently of all others. While any number of separate timers may be used, the drawings show four. Since all 20 are alike, description of one will apply to and suffice for all.

These timing devices are frequently used to control the operation of one or several machines, particularly machines which are started, independently of the timer, either automatically or by operator control which also initiates operation of the timer, which at the conclusion of the operation, stops the machine, for example, and also resets the timer to zero position, ready for

another operation. When several machines are controlled, more or less individually or independently of each other, the timer obviously must be located at a convenient central point with some communication to and from each machine.

35 Thus, the timer includes a timer controller or operator to initiate its action and which is controlled from the machine or the governor therefore, and also a controller for the machine, such as to stop it, actuated by the timer. These two 40 controllers, in the timer, may be servomotors of either the electrical or fluid pressure form, both being convenient for use in remote control. For example, the timer controller servomotor may be a solenoid or electromagnet and the machine controller an electric switch. The drawings, however, show the timer, or one unit thereof, arranged to control a fluid pressure operated system, and more particularly such a system of a conventional garment press later described more

50 in detail. The two controllers, therefore, are of fluid pressure form.

The timer controller (Fig. 2) is a fluid pressure servomotor 15, supplied with pressure through conduit 16, the diaphragm of which motor actuates a plunger 17, the free end of which abuts and

operates one arm of a bell crank lever 18 (Fig. 3).

The machine controller is a normally closed valve 19 controlling the flow of fluid pressure, e. g. air pressure, from a manifold 20, to which all timer units are connected, supplied by a conduit 21 communicating with a source of fluid pressure (not shown). This valve is actuated by a finger 22, later referred to.

The active mechanism of each timer unit includes the two members of a friction clutch, which normally lie in clutch-open or uncoupled relation, toward which they are biased. The driving member of the clutch couple is a disc 23 fixed to shaft 11, as by set screw 24, and provided with a facing 25 of friction material. This operates with the like facing 26 on a driven disc 27 loosely rotatable upon and slidable longitudinally along the shaft. Disc 27 is biased toward the right in Fig. 3 by compression spring 28 so that it always hugs or abuts the second and forked arm of bell crank lever 18 actuated by servomotor 15.

Alongside disc 27 is a stationary plate or support 29 of channel form, reinforced by edge flanges 30 and attached to the base 10. To this plate is connected at 31a one end of a spiral coiled spring 31, like a clock spring, the other end of which is attached at 31b to finger 22, before referred to, attached to driven disc 27.

In Fig. 2 shaft 11 rotates counterclockwise, and spring 31 is of such form, and is so tensioned, that it always tends to turn disc 27 clockwise, or in the opposite direction from that of shaft rotation.

Each unit of the timer is enclosed between two sections 32 of a housing or cover, said sections being spaced apart to provide a slot along which may be adjusted a stop device 33 capable of being clamped in any desired position by the binding nut 34. A scale 35 may be inscribed alongside each slot, with divisions indicating time intervals.

The drawings show one unit of the timer, say the fourth from the left in Fig. 1, conventionally indicated by the dot-dash rectangle A in Fig. 4, connected to time or control the pressure period of a laundry or garment press of conventional form. This comprises a frame 40 on which is mounted a bed 41 cooperating with a pressing head 42 carried by a pivoted lever 43 connected to the upper of two toggle links 44, 45 the lower of which is pivoted to the bed. The press is opened by a tension spring 46 and is closed by supplying fluid pressure to a motor 47 the piston of which is connected by rod 48 to the toggle knuckle. After the press is closed heavy power pressure is applied to the work by the effort of the piston 49 of a power motor 50, said piston being connected by rod 51 to the bed, which it elevates.

The press is controlled by two manually operable supply valves 60, 61 in series, an exhaust valve 62, capable of operation either by a manual 63 or by pressure supplied to a small servomotor 64, effective upon said manual, and a pressure maintaining supply valve 65, actuated by servomotor 66.

The operation is as follows:

The drawings show the press closed under full pressure, with the parts of the timing mechanism ready to release or open the press. However, assuming motor 14 in operation and the press wide open, the pistons of the two motors 47, 50 are full retracted; servomotors 15, 64, 66 are inactive; valves 19, 60, 61, 62 and 65 are

closed; clutch 25, 26 is released; and finger 22 is held against stop 33 by spring 31. In Fig. 2, stop 33 is shown adjusted to a position about 90° from the stem of valve 19. Since shaft 11 rotates at 1 R. P. M. that means that it requires about 15 seconds for the finger to reach the valve stem, when the timer unit is energized. By adjusting the stop to other positions, or by using a different ratio of speed reduction and driving shaft 11 at other speeds, any desired time delay interval may be secured.

Now, assuming the stop 33 has been adjusted to the proper position, with finger 22 held against it, as described, the press is closed by opening both supply valves 60, 61. Fluid pressure flows from the supply pipe 67 through said valves and exhaust valve 62 to pipe 68 and thence to the cylinder of motor 47, moving over its piston, straightening or closing toggle links 44, 45 and closing the press, under light pressure, if any.

As the piston of motor 47 nears the end of its travel communication is established to pipes 69, 70. Pipe 69 supplies pressure to motor 50, which completes press closing under heavy pressure. Pipe 70 supplies pressure to the servomotors 66, 15.

Servomotor 66 actuates valve 65, which supplies maintaining pressure from pipe 71 to pipe 16, and through pipe 70 to motors 47, 50, thus enabling the operator to release the manuals of valves 60, 61.

Pipe 16 supplies pressure to actuate servomotor 15 of the particular timing unit involved, the effect being to close the clutch faces 25, 26 into driving relation. Thereupon disc 27 begins to turn with disc 23, its travel continuing during the selected time interval, at the end of which finger 22 engages the stem of valve 19 and opens said valve. This operation supplies pressure from pipe 21 to pipe 14 and thus to motor 64, which operates to actuate the manual 63 and open exhaust valve 62. Thereupon all pressure is evacuated from servomotors 15 and 66 and from motors 47, 50. The press promptly opens and since the pressure of servomotor 15 upon lever 18 has been relieved disc 27 moves away from disc 23 and the clutch opens. Thereupon spring 31 returns finger 22 to its original position against stop 33.

If other timing units are connected to and operated by shaft 11, and are operatively associated with other machines, such as presses, those presses may be operated, independently of the press shown, with individual control of each by its own timer, in the manner described. Of course, when several presses are arranged and operated in special association with each other, as in the several presses of a shirt unit, those presses may have their controls connected for tandem operation, according to standard practice, without interference with or by the timing mechanism here involved.

The apparatus described is simple and highly efficient and readily may be applied either to new presses or to old presses already in service.

Other advantages of the invention will be apparent to those skilled in the art.

What I claim is:

Timing apparatus of the character described comprising a continuously rotatable driving shaft, pilot motor means for rotating the same, a driving clutch member fixed to the shaft to rotate therewith, a co-operating driven clutch member rotatably mounted on the shaft, and also movable axially thereon within limits for

movement into and out of coupled relationship with its mated fixed clutch member, helical spring means between said mated clutch members disposed to bias said driven clutch member toward uncoupled relation, a work controlling fluid pressure motor, manually operatable valve mechanism in fluid flow communication with said motor for controlling the flow of pressure thereto for energizing the same, lever means engageable with said movable clutch member to move the same into coupled relationship with its mate, a second fluid pressure motor effective, when energized to operate said lever means, said first and second named fluid motors being respectively successively responsive to said manually operatable valve mechanism, a fixed valve device in fluid flow relationship with said first named fluid motor and located in the path of advance rotation of the driven clutch member, said driven clutch member having a valve operating finger fixed thereon and operable thereby for contacting said valve and exhausting the pressure from said first named motor to de-energize the same, said second named motor being in fluid flow relationship with said first named motor whereby to be exhausted therewith, coil spring means having one end fixed and the other end connected to said movable clutch member and biased to cause rotation of

5 said movable clutch member in the reverse direction to driven movement thereof whereby, when the mated clutch members are disengaged by exhaust of said second named fluid pressure motor, operation of said helical spring returns said driven clutch member to its initial position ready for another operation, and adjustable stop means in the path of and adapted to intercept said valve operating finger during 10 reverse rotation of said driven clutch member whereby such reverse rotation is adjustably predetermined and limited, to thereby control the arc of driven travel of said driven clutch member during which travel the said first fluid pressure motor is effective.
